UNITED STATES PATENT OFFICE.

CHRISTOPHER MARXMILLER, OF SHELBYVILLE, ILLINOIS.

METAL-CUTTING SHEARS.

SPECIFICATION forming part of Letters Patent No. 761,314, dated May 31, 1904

Application filed September 14, 1903. Serial No. 173,134. (No model.)

To all whom it may concern:

Be it known that I, CHRISTOPHER MARXMILLER, a citizen of the United States, residing at Shelbyville, in the county of Shelby and State of Illinois, have invented certain new and useful Improvements in Metal-Cutting Shears, of which the following is a specification.

My invention relates to improvements in metal-cutting shears; and the main object of my invention is the provision of a device of this character which will cut metal any thickness—that is, sheet metal to bar metal—and do so in a perfect manner and with comparative ease.

Another object of my invention is the provision of a metal-cutting shears which is the embodiment of simplicity, durability, and cheapness, thus producing a thoroughly efficient and practical device.

In the drawings, Figure 1 is a side elevation of the shears open ready to receive the metal to be cut. Fig. 2 is a side elevation taken from the opposite side with the jaws closed after having made a cut. Fig. 3 is a detail view of the movable jaw and connections disconnected. Fig. 4 is a section through the eccentric and connections.

Referring to the drawings, A designates the base, which is adapted to rest upon any suitable place or may be bolted down to insure against the movement thereof when making heavy cuts. Formed integral with the base and extending upward therefrom is the plate or large strip or rib B, which is provided with the recess or slot C to receive the removable stationary cutter-blade D, which is securely held in place by means of the brace or clamping-plate E. Pivots connected to the rib, near one end thereof, by means of the bolt F, is the removable jaw or member G, which is provided with the recess or slot H similar to the slot C and which when the jaw is closed is substantially in line therewith. Mounted in said recess and removable therefrom is a cutter-blade J, which is held in said recess by means of the brace or clamping-plate K. The arm M is connected pivotally in the slotted end N of the jaw G, the ring or collar P being formed integral with the arm

M. This ring or collar surrounds the eccentric Q, carried by the shaft L, so that when the handle O is operated the shaft L is rotated, in turn operating the arm M, and consequently the jaw G.

From the foregoing description, taken in connection with the drawings, the usefulness and operation of my improved shears is readily understood and its numerous advantages are fully appreciated.

It is evident that I provide a metal-cutting shears which are very simple, durable, and inexpensive in construction and thoroughly efficient and practical in use.

What I claim as new, and desire to secure by Letters Patent, is—

1. A metal-cutting shears, comprising a base, a strip or rib at right angles thereto, a cutter-blade carried by said strip, a pivotally-mounted jaw connected to said strip, a cutter-blade carried thereby, an eccentric-arm connected to said jaw and strip, and a handle for operating the arm to open and close the jaw.

2. A metal-cutting shears, comprising a base, a strip rising therefrom and provided with a recess in its upper edge, a cutter-blade removably attached in said recess, a jaw pivotally connected to said strip and provided with a recess in its lower edge opposite the recess of the strip, a cutter-blade removably attached in said recess, an eccentric-arm connected to said jaw and strip, and a handle for operating the arm to open and close the jaw.

3. A metal-cutting shears comprising a base, a strip rising therefrom provided with a recess in its upper edge, a clamping-plate removably secured to said strip and opposed to said recess, a cutting-blade carried by said clamping-plate, and fitting in said recess, a jaw pivotally connected to said strip and provided with a recess in its lower edge adapted to align substantially with the recess of the strip when the lower edge of the jaw is substantially parallel with the upper edge of the strip, a clamping-plate secured to said jaw and opposed to the recess, a cutting-blade carried by said clamping-plate fitting in said recess, and means for opening or closing said jaw for the purpose set forth.

4. A metal-cutting shears, comprising a base, a strip rising therefrom provided with a recess in its upper edge, a clamping-plate removably secured to said strip and opposed to said recess, a cutting-blade carried by said clamping-plate and fitting in said recess, a jaw pivotally connected to said strip and provided with a recess in its lower edge mounted to align substantially with the recess of the strip when the lower edge of the jaw is substantially parallel with the upper edge of the strip, a clamping-plate secured to said jaw and opposed to the recess, a cutting-blade carried by said clamping-plate fitting in said recess, a shaft journaled in the strip, an eccentric carried by said shaft, a ring surrounding said eccentric and provided with an arm which is pivotally connected to the free end of the jaw, and a handle connected to the shaft for rotating the same to operate the jaws.

5. A metal-cutting shears, comprising a base, means carrying a cutter supported by the base, a pivotal jaw pivotally connected to said means, a cutter carried by said jaw, a

shaft journaled in the base, an eccentric carried by said shaft, a ring surrounding said eccentric and provided with an arm which is pivotally connected to the free end of the jaw, and a handle connected to the shaft for rotating the same to operate the jaws.

6. A metal-cutting shears, comprising a base, a strip rising therefrom at right angles thereto, a cutter-blade removably carried by said strip, a jaw pivotally connected to said strip, a blade removably carried by said jaw, a shaft journaled in the strip, an eccentric carried by said shaft, a ring surrounding said eccentric and provided with an arm which is pivotally connected to the free end of the jaw, and a handle connected to the shaft for rotating the same to operate the jaws.

In testimony whereof I affix my signature in presence of two witnesses.

CHRISTOPHER MARX MILLER.
